UNITED STATES PATENT OFFICE.

ROSCOE C. IDDINGS, OF DAYTON, OHIO, ASSIGNOR TO FYR-FYTER COMPANY, OF DAYTON, OHIO, A CORPORATION OF OHIO.

FIRE EXTINGUISHER.

Application filed February 13, 1917. Serial No. 148,309.

To all whom it may concern:

Be it known that I, Roscoe C. Iddings, a citizen of the United States, residing at Dayton, county of Montgomery, and State 5 of Ohio, have invented certain new and useful Improvements in Fire Extinguishers, of which the following is a full, clear, and exact description.

This invention relates to improvements 10 in fire extinguishers and is in particular an improvement on the fire extinguisher illustrated and described in application Serial No. 137,560, filed December 18, 1916, by T. M. Dunlap. In their present embodiment 15 my improvements form part of a fire extinguisher which is in general similar to that disclosed in the above mentioned application and the purpose of my improvements is to render devices of the kind more simple and 20 inexpensive in construction; to eliminate certain requirements in operation, so that even in the excitement usually attending the operation of such devices no delay may be caused by the operator forgetting just how 25 to operate it; by eliminating certain exterior parts and providing protection for others, thereby reducing the danger of damage which might disable the device.

In the drawing forming a part of this 30 specification, and wherein the preferred embodiment is illustrated, Figure 1 is a longitudinal central section of an extinguisher embodying the invention.

Fig. 1^A shows a fragment of Fig. 1, some- 35 what enlarged, the parts being shown in elevation instead of section.

Fig. 2 is an end elevation of the extin- 40 guisher.

Fig. 3 is an enlarged detail section illus- 45 trating more particularly parts of the air pump.

Fig. 4 is an enlarged transverse section of 50 the pump, taken on the line 4—4 of Fig. 3.

Fig. 5 is a sectional view similar to Fig. 1 55 but taken in a different plane to more clearly illustrate one of the valves and the means by which it is controlled from the handle.

Figs. 6 and 7 are enlarged, transverse sec- 60 tional views taken substantially on the lines 6—6 and 7—7 of Fig. 5.

Fig. 8 is an enlarged detail section taken 65 substantially on the line 8—8 of Fig. 6, and illustrating more particularly the valve mechanism for controlling the intake and discharge of the liquid.

Fig. 9 is a view similar to Fig. 8 but taken at right angles thereto, on line 9—9, Fig. 6.

Fig. 10 is a transverse sectional view of the valve casing, taken on the line 10—10 of Fig. 8.

60

Fig. 11 is a broken, detail sectional view taken on the line 11—11 of Fig. 2.

65

Fig. 12 is an elevational view of parts illustrated in Fig. 11, looking from the right of the latter.

Fig. 13 is a detail sectional view taken substantially on the line 13—13 of Fig. 11; and

65

Fig. 14 is a detail perspective of one of the parts employed in the valve mechanism.

70

In said drawing, 20 denotes a container for the fire extinguishing liquid and various operating parts, the container being shown as of cylindrical form. Within said container is located the air pump device design- 75 ated generally by the reference A; valve controlling mechanism designated generally by the reference B; and intake tubes or pipes designated generally by the reference C.

The air pump, as shown, comprises a cy- 80 lindrical tube 21 secured at its outer end within a suitable recess formed on the inner face of the cast end 22 of the container, said tube or cylinder 21 being closed at its inner end by a plug 23, the latter having an 85 extension 24 centrally recessed to receive a perforated, threaded nut 25 for retaining a ball check valve 26 and spring 27 controlling the position of the ball.

Slidably mounted within the tubular cyl- 90 inder 21 is a hollow piston rod 28 having secured thereto, at its inner end, a piston 29 to which is secured an outer, cup-shaped leather washer 30, the washer being kept in tight engagement with the cylinder by 95 means of an annular coiled spring 31 seated in a suitable annular recess formed in the piston 29. The piston 29 is centrally perforated as indicated at 32 so as to communicate with the interior of the piston rod 28,

100 and mounted within said perforation 32 is another ball check valve 33 with which co- operates a spring 34. The inner end of the spring 34 bears against a disc 35 having an extension 36 threaded to the piston 29. The 105 disc 35 is shown as provided with four radially extending openings 37 which communicate with the interior of the cylinder. Also mounted within the cylinder 21, at its 110 inner end, is a packing ring 38 against which

the disc 35 is adapted to bear when the piston is in its innermost position, to thereby seal the passageway between the interior of the cylinder 21 and the interior of the container. The piston rod 28 is extended through a boss 39 on the end casting 22 and at its outer end carries the operating handle 40. It will also be noted from an inspection of Fig. 1 that the piston rod 28 is 10 provided with a pair of openings 41, 42 for the purpose hereinafter described.

As will be apparent from the preceding description, upon outward movement of the operating handle, the check valve 26 will remain closed and air will pass through either 15 of the openings 41 or 42 through the hollow piston rod 28 and to the underside of the piston through the check valve 33. Upon forcing the piston inwardly, the check valve 33 20 will be automatically closed and air will be forced through the passageway in the plug 23 past the check valve 26, and thus into the container 20, thereby storing compressed air in the container for the purpose of forcing 25 out the liquid, as hereinafter described.

Referring now more particularly to Figs. 1, 5, 8, 9, 10 and 14, the valve mechanism for controlling the intake and discharge of the liquid from the container is shown as comprising a preferably die pressed casing 43 soldered or otherwise secured to the pump cylinder 21 and located near the center of the container. The casing 43 is provided with valve chambers 44-44 at the ends thereof 30 and a larger central chamber 45. The chambers 44-44 are separated from the central chamber 45 by partitions 46-46. Mounted within each chamber 44 is a valve 48 having a stem 49 which extends through an opening 47 in the partition 46, it being understood 35 that the stem is adapted to slide in said openings, the walls of which are grooved, as in Fig. 10. In Figs. 8 and 9, the right hand valve 48 is shown as seated on its seat and the left hand valve 48 is shown in open position. Each of the valve chambers 44 is closed at 40 its outer end by means of a sheet metal plate 50, secured to the casing 43. Each of the valve stems 49 is provided with an annular 50 groove 51, over which is seated one of the forked ends 52 of a connector 53, the latter being shown in detail in Fig. 14. By means of the connector 53 the valves 48 are operated in unison and are held in such relation to 55 each other that as one valve 48 assumes a closed position the other is moved to open position. In order to render the operation of the valves 48 more sensitive a heavy ball 54, preferably of lead, is loosely mounted within 60 the casing 43 and between the forked ends of the connector 53. The connector slides in a channel formed in one side of the chamber 45 (see Fig. 6), which prevents the ball resting on the connector. Friction which the 65 ball resting on the connector might create is

thus prevented and the ball is consequently more effective to actuate the valves.

From the preceding description, it will be seen that as the fire extinguisher is tilted from the horizontal, the ball 54 will roll to 70 the lowermost position in the chamber 45 and thereby open the then lower valve 48 and cause the then upper valve 48 to close. Upon the extinguisher being tilted with its other end up, the ball will roll to the opposite end of the chamber 45 and reverse the 75 positions of the valves 48.

In order to discharge the liquid from the container when air pressure is created therewithin, the flexible intake tubes C-C are 80 provided, each of which has its inner end connected to one end of the casing 43. Each tube C is preferably flexible throughout and air-tight. At its outer or free end, each tube C has attached thereto an intake mouth or member 55, made preferably of some heavy material such as lead or the like. Each intake member 55 is provided with a central passageway 56 communicating with the flexible tube C and attached to each member 55 85 is one or more rings 57 of felt or other suitable soft material, the latter being employed to prevent the heavy mouth piece from denting the casing 20 and also to eliminate noise or rattle. As clearly appears from Figures 90 1 and 5 the inner ends of the tubes C are secured to the casing 43 substantially in line with the axis of the container 20 so that, as the container is rotated, the mouth pieces 55 will follow the contour of the container 95 and automatically maintain themselves in the lowermost position within the container to thus insure complete discharge of the liquid regardless of the position of the extinguisher. 100

Each of the tubes C is in communication with a valve chamber 44 so that, depending upon which of the valves 48 is open, the liquid will be forced up through the corresponding tube C, past the open valve 48 and into the central chamber 45. From the latter leads a discharge passageway 58 (see Fig. 8), the latter communicating with a short pipe 59 that in turn communicates with a chamber 60 formed in an extension 61 115 preferably cast integrally with the end 22. Mounted within said chamber 60 (see Fig. 5) is a discharge controlling valve 62 secured to the inner end of a rod 63, the latter being extended to the exterior of the container through a packing gland 64. Mounted on the rod 63 is a spring 65, which bears at one end against said valve 62 and at its other end against shoulder 66. Communicating with the chamber 60 is an outlet 67 that in turn 120 communicates with the discharge pipe 68, the latter having a discharge nozzle 69 at the end of the container 20. The valve 62 is shown in Fig. 5 in its normal position and bears against a packing ring 62^a to seal the 130

outlet passage 67. This ring is made of some yielding substance, cork for example, and is made rather thick, for a reason to be herein-after referred to.

5 The position of the valve 62, which I also call the sealing valve, is controlled by the operating handle 40, the latter being provided with a cam groove having the oppositely arranged portions 70—70 and the 10 central portion 71, with which engages a knob 72 secured to the outer end of the rod 63. When the handle is in the position shown in Figs. 5 and 11, the knob 72 rests on the high point 71 of the cam groove; 15 the valve 62 is thereby held in closed position. By turning the operating handle 40 in either direction, the knob 72 is either forced inwardly or moves inwardly under the influence of the spring 65, thereby opening 20 communication between the pipe 59 and passageway 67. The valve 62 is maintained in this open position by means of the spring 65. In order to prevent the handle 40 from being pulled out when it is in engagement 25 with the knob 72, the handle is provided with a short inwardly extending flange 73 which engages under a flange 74 which extends laterally from the boss 39 on the end 22 of the container. These flanges keep the 30 disk 35 firmly seated on the packing ring 38. This ring is composed of some yielding substance, cork for example, and the parts are so proportioned that when flange 73 is under flange 74 the packing ring 38 will 35 be somewhat compressed, thus insuring a good seal. The ends of flange 73 are beveled as at 73^a, Figs. 1 and 1^a, so as to cam the piston inward as it is locked in closed position and press the disk 35 against the 40 packing ring 38. As the handle 40 is rotated to disengage the knob 72 the flange 73 will also be disengaged from the flange 74, whereupon the handle with the piston secured thereto may be reciprocated to force 45 air into the container. The portion 71 of the cam groove 70—70 is slightly depressed (see Fig. 12) and when this depression comes under the knob 72 the knob falls into it and acts as a sort of friction lock, tending 50 to prevent the handle from rotating. The packing ring 62^a, against which valve 62 bears, is thick enough to yield a considerable distance. This permits of enough compression so that when the knob 72 drops 55 into the depression 71, part of the compression of the packing ring being thereby lost, there remains enough compression to make a tight seal.

The container may be filled by removing 60 the threaded plug 75, a soft metal washer 76 being preferably interposed between the head of the plug 75 and the end wall 22. From the preceding description, it will 65 be seen that so long as the operating handle

tion, communication between the outside of the container and the interior is prevented by the valve 62 and the seal formed between the disc 35 and packing ring 38. Less perfection is therefore required in the check 70 valve 26. Whenever it is desired to use the extinguisher, all that is necessary for the operator to do is to turn the handle 40 in either direction and then reciprocate the same, thus creating the pressure within the 75 container. As the fluid is expelled by air pressure instead of by the direct action of the pump a continuous stream is thrown from the nozzle as long as there is sufficient air pressure. If desired the operator may 80 hold his finger over the nozzle and pump a considerable pressure, then by locking the handle in its inward position retain this pressure. He can then carry the extinguisher to a place where he wishes to use it, which 85 may be where it would be inconvenient to operate the pump, and by simply turning the handle the liquid will be expelled by the pressure without operating the pump. The pump handle being unlocked by rotation in 90 either direction practically eliminates the possibility of delay through confusion of the operator in the excitement almost certain to attend the use of the device. The parts are so proportioned that opening of 95 the valve 62 occurs while the flange 73 on the handle is still confined under the flange 74, so that the seal between the disk 35 and packing ring 38 is maintained while the 100 contents of the container is being expelled by air pressure previously pumped up. By turning the handle to the right or left a steady stream can be played on a fire, the strength of the stream being controllable by turning the handle more or less. By means 105 of the flexible intake tubes C, the mouth of at least one of the latter will always be in the lower most position of the container and will automatically shift its position under the influence of gravity, no matter to what 110 position the container is shifted. The parts are of simple construction and may be assembled on the end member 22 before the latter is secured to the container, with the exception of the nozzle 69 which can easily 115 be applied after all the other parts are in position. Forming the boss which supports the pump cylinder, and the valve chamber 61 integral with the end member 22 materially strengthens and simplifies the structure and reduces to the minimum the 120 chances for trouble from leaky or loose joints. It also makes possible a lighter construction, thereby reducing the total weight of the extinguisher materially. The handle 125 40, particularly the part thereof which contains the grooves 70—70, affords a considerable measure of protection for the valve stem 63 and knob 72; then when the handle is unlocked the valve moves inward and 130

leaves nothing but the knob exposed, which is still considerably protected by the piston. As these are the only external parts of the mechanism, the danger of mechanical injury to the device is very slight.

To prevent tampering with the extinguisher the several operative parts may be secured by a light wire secured by a seal. This is illustrated in Fig. 2 where the wire 10 80 is threaded through an aperture 81 in the plug 75 (see Fig. 1), through an aperture 82 in the knob 72 and an aperture 83 in the handle 40 (see Figs. 5 and 11). The wire may be light enough to be easily 15 broken by anyone needing to use the extinguisher, and until broken it furnishes evidence that the extinguisher has not been tampered with.

Although the device herein shown and 20 described in detail is considered the preferred embodiment of the invention, the same is merely illustrative and all changes and modifications are contemplated that come within the scope of the claims appended hereto.

What I claim is as follows:

1. In a device of the character described, comprising a container, a pump and a valve, in combination; means for locking the 30 pump piston to prevent longitudinal movement, said means being operable to unlock the piston by rotating the piston in either direction, and means for operating the valve by said rotation of the piston, whichever direction it is rotated.

2. In a device of the character described, comprising a container and a pump, means for locking the pump piston to prevent longitudinal movement in one direction, 40 said means being operable to unlock the piston by rotating the piston in either direction, and means whereby the piston is forced longitudinally a slight distance in the opposite direction by the act of locking it.

3. In a device of the character described, comprising a container, a pump and a valve, the piston rod of the pump and the valve stem being the only exposed operative parts, in combination; a handle attached to the 50 piston rod whereby it is reciprocated, and means integral with the handle for operating the valve when the handle is rotated.

4. In a device of the character described, a container, a pump therein, the piston rod 55 of which extends to the exterior, a reciprocating valve, the stem of which extends to the exterior and carries a knob, and a handle carried by the piston rod having a cam adapted to engage said knob and operate the valve.

5. In a device of the character described, a container, a pump therein, the piston rod of which extends to the exterior, a reciprocating valve, the stem of which extends to

the exterior and carries a knob, and a handle 65 carried by the piston rod of the pump having a cam adapted to engage said knob and operate the valve, the highest part of said cam having a slight depression which receives the knob and tends to oppose movement of the handle.

6. In a device of the character described, a container, a pump adapted to store air under pressure in the container, a port in the end of the pump cylinder, a packing 75 ring composed of yielding substance surrounding said port, a valve member carried by the pump piston and adapted to co-operate with said ring to cut off communication between the pump cylinder and the 80 interior of the container, means for holding said valve member against the ring when the pump is not in operation; said means being operable by rotating the handle; a discharge nozzle, a valve to control the discharge therefrom and means whereby said valve is opened or closed by rotating the handle, said opening and closing being timed to occur while said valve member is 85 in engagement with said ring.

7. In a device of the character described, a container, an outlet therefor, a pump for expelling the contents from the container, a flexible intake pipe connected to the outlet, one end of the pipe being free to seek its own position in response to gravity, the end thereof being weighted to make its self-adjustment more positive, and a cushion of 95 felt or other soft substance surrounding said weighted end to prevent noise and injury 100 to other parts of the device.

8. In a device of the character described, a container, two intake pipes, a discharge pipe common to both intake pipes, and gravity valve mechanism adapted to cut one 105 or the other of the intake pipes off from the discharge pipe; said mechanism comprising a valve for each intake pipe, a member connecting said valves so that they move in unison, and a weight adapted to roll by 110 gravity into contact with one or the other of said valves and operate it, said connecting member operating the other valve simultaneously but conversely, and means for isolating the weight from the connecting 115 member so that its weight shall not add to the friction of the connector and thus impede its movement.

9. In a device of the character described, a container, a receiving chamber within the 120 container, two intake pipes connected to said chamber, a gravity valve adapted to cut off each pipe, a connector whereby said valves are connected and made to operate in unison, said connector being arranged to 125 slide in a channel formed in one side of the chamber, and a ball confined in the chamber and adapted to roll against and op-

erate one or the other of the valves, the connector operating the other valve simultaneously but conversely, the ball being prevented from resting on the connector by the latter being in the channel.

10. In a device of the character described, a container, a pump therein, the piston rod of which extends to the exterior, a reciprocating valve, the stem of which extends to the exterior and carries a knob, and a handle carried by the piston rod of the pump having a cam adapted to engage said knob and operate the valve, the highest part of said cam having a slight depression which re-

ceives the knob and tends to oppose movement of the handle, said valve comprising a compressible valve seat having sufficient range of compression and resiliency to permit the highest part of the cam to pass the knob and yet insure a tight closure when the knob rests in the depression.

In testimony whereof I affix my signature in the presence of two subscribing witnesses.
